UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,597, dated August 28, 1894.

Application filed July 31, 1894. Serial No. 619,103. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of groups of flowers and leaves placed at uniform distances 10 apart with flowing ribbons attached to said groups of flowers and leaves, and between said groups of flowers and leaves are placed at regular distances apart in a vertical line small ornaments as represented in the accompanying drawing. The border or upper portion of

the design is formed of a series of pendent groups of flowers and leaves connected by a festoon of ribbon with an ornamental band at the bottom as represented in the drawing.

What I claim is—

1. The design for wall paper herein shown and described.
2. In the design for wall paper the border herein shown and described.

Witness my hand this 28th day of July, 25 1894.

CHARLES BOOZE.
